UNITED STATES PATENT OFFICE.

HENRY DAVENPORT, OF PHILADELPHIA, PENNSYLVANIA.

DESIGN FOR GIMP.

SPECIFICATION forming part of Design No. 12,052, dated December 7, 1880.

Application filed October 26, 1880. Term of patent 7 years.

To all whom it may concern:

Be it known that I, HENRY DAVENPORT, a subject of the Queen of Great Britain and Ireland, residing in Philadelphia, Pennsylvania, have invented a new and original Design for Gimp, of which the following is a specification.

My design for gimp is fully illustrated in and by the accompanying drawings, in which—

10. Figure 1 is a view of the strip of gimp, and Fig. 2 a detached view of one of the principal features of the design.

The gimp, a strip of which is shown in Fig. 1, may be of different widths, but is generally about half the width shown in Fig. 1, which is drawn to an enlarged scale in order to fully illustrate its details.

The most prominent features of the design are the ornaments A, which are fully illustrated in Fig. 1, and in the detached view, Fig. 2, these ornaments being arranged at uniform intervals throughout the gimp, which has a central stripe, b, the continuity of which is interrupted at intervals by the ornaments A.

The opposite edges of the gimp are scalloped, 25 as shown, and between each scalloped edge and the system of ornaments intervenes a narrow stripe, d.

Irrespective of the colors used in carrying out the design, I claim—

1. A gimp design consisting of a succession of ornaments, A, substantially as described and shown.

2. The gimp design, consisting of a succession of ornaments, A, and a center stripe, b.

3. The gimp design, consisting of the ornaments A, central stripe, b, and stripes d.

4. The gimp design, consisting of the scalloped edge of the gimp, ornaments A, and stripes, substantially as shown and described.

In testimony whereof I have signed my name to this specification in the presence of two subscribing witnesses.

HENRY DAVENPORT.

Witnesses:

JAMES F. TOBIN,

HARRY SMITH.
